SYLVANIA, A CORPORATION OF NEW JERSEY.

DRAIN CONNECTION.

No. 928,082.

Specification of Letters Patent.

Patented July 13, 1909.

Application filed January 14, 1909. Serial No. 472,212.

To all whom it may concern:

Be it known that we, EDWARD L. DAWES, of New Brighton, Beaver county, Pennsylvania, and JOHN C. REED, of Pittsburg, 5 North Side, Allegheny county, Pennsylvania, both citizens of the United States, have invented a certain new and useful Drain Connection, of which the following is a specification.

10 Our invention relates to drain connections for sinks, tubs, basins and the like.

Throughout this specification for the sake of brevity we will describe the invention as used in connection with a sink, but it is to be 15 understood that the invention is applicable equally well to tubs or any other tublike vessels.

Our invention is designed to be used principally in connection with high-grade sinks 20 or tubs, the inner surfaces of which are covered with vitreous enamel. Because of the character of the drain connections which have heretofore been used on enameled sinks, it has been considered necessary to 25 provide a recess in the sink bottom surrounding the drain opening. It is exceedingly difficult to properly enamel metal surfaces having abrupt angles such as are found in sinks provided with such a recess. In applying the drain connection to sinks having 30 such a recess, the enamel adjacent to the opening is frequently cracked or crazed for reasons understood by those skilled in this art. Our invention avoids these disadvantages by providing an enameled sink with a 35 straight walled drain opening, the upper edge of which immediately joins the normal inner bottom surface of the sink. The said sink surface may be made entirely free from 40 sharp angles or abrupt changes in direction. The parts of the drain connection which are originally separate from the sink are adapted 45 to the style of the sink bottom and drain opening described and the connection is further constructed and arranged so that the 50 entire fluid contents of the sink may be discharged through the drain opening, there being no recess or trap formed within the sink by any part of the appliance which retains any portion of the fluid.

In carrying out our invention in a pre-

ferred form, certain parts of the appliance protrude above the normal inner bottom surface of the sink.

One of the objects provided for by the invention is to provide means in this kind of a drain connection by which the waste water may be strained and at the same time substantially every drop of the fluid may pass out through the drain opening. 55

The use of our invention avoids any tendency to chip or craze the enamel surrounding the drain opening and at the same time the appearance of such portions of the connection as may be seen from within the sink is 60 very ornamental and attractive. 65

In the accompanying drawing we show an exemplifying structure embodying the invention, but it is to be understood that the invention is capable of embodiment in different forms. 70

Figure 1 is a vertical section through a portion of a sink and drain connection. Fig. 2 is an elevation of the connection, the sink bottom being shown in section on the center 75 line of the drain opening. Fig. 3 is a top view of the nipple removed from the other parts of the appliance. Fig. 4 is a top view of the strainer by itself.

Reference character 1 designates a sink or 80 the like, 2 the customary approximately level and horizontal inner bottom surface thereof, and 3, the drain opening, usually circular, having a perfectly straight cylindrical wall passing through the bottom of the sink. 85

The drain opening is generally surrounded at the outside of the sink bottom with a circular boss 4 to increase the thickness and strength of the sink bottom at this point. Sinks or tubs of the class with which this invention is generally employed are usually 90 covered on their inner surface with vitreous enamel but the invention is also applicable to vessels which are not so enameled and for this reason and for the sake of clearness it is 95 not attempted to show the enamel in the drawing. It is to be noted especially that the inner bottom surface of the sink preserves its normal contour directly to the drain opening and has no abrupt changes of 100 direction or recesses other than the drain opening itself. It is possible for this reason

to perfectly enamel the sink bottom directly up to the drain opening on the plain or even surface without the depression or recess, thereby preventing the loss occasioned by 5 this irregular shape of the recess either in manufacture or after the article has been in use.

A nipple 5 provided with radially extending fingers 6 is passed through the drain opening so that the cylindrical portion of the nipple 7 extends below the bottom portion of the sink. The fingers then rest upon the inner bottom surface of the sink adjacent to the opening. The tubular portion 7 is exteriorly threaded and a nut 8 engaging the thread compresses a gasket 9 against the boss 4 forming a water seal. The tubular portion of the nipple is discontinued considerably below the inner bottom surface of the sink and 15 the fingers 6 are widely separated as may be seen in Fig. 3 so that the nipple itself offers no perceptible resistance to the flow of water even at its lowest level through the drain opening. The nipple 5 has a cross-bar 10. 20 The strainer 11 is of inverted dish shape and preferably has a substantially flat top. The substantially vertical side 12 of the strainer is just deep enough to touch the inner bottom surface of the sink and enable the top of 25 the strainer to rest on the tops of the finger 6. At the center the strainer is depressed in making it, or countersunk to receive a screw head and a screw 13 passes through the strainer at this point and engages a threaded 30 opening 14 formed in cross-bar 10. The screw-head rests in the countersink flush with the upper surface of the strainer. The strainer has top openings 14 through which the bulk of the water passes, and side openings 15 which extend to the inner bottom surface of the sink and permit the escape of water after its level is lower than the top of the strainer. Without these side openings in this kind of a drain connection some of the 40 fluid would be trapped in the tub by the strainer.

The drain pipe 16 may be connected to the nipple in any convenient way but in a preferred construction the pipe is provided with 50 a flange 17 which rests against the end of the nipple and a nut 18 engaging the screw thread on the nipple has a flange 19 inwardly extending and engaging flange 17 and serving to urge the latter tightly against the end of the nipple.

We claim:

1. The combination of a sink or the like, having an approximately horizontal bottom pierced with a straight drain opening immediately joining the normal inner surface of the sink bottom, and a drain connection applied to the sink at said opening including members engaging the inner surface of the sink bottom adjacent to the opening, a tubular portion carrying said members and ex-

tending through the opening, a nut threaded on the tubular member below the outer bottom surface of the sink, a fluid seal between the nut and the outer bottom surface of the sink, and a strainer near the top and overlying the said connection, the elements of the combination being constructed and arranged so that the entire fluid contents of the sink may be discharged through the drain connection. 75

2. The combination of a sink having a substantially smooth level, horizontal, inner bottom surface and provided with a straight circular drain opening through the bottom, the edge of the opening immediately joining the normal inner bottom surface of the sink, a nipple passing through the opening and provided with fingers engaging the inner bottom surface of the sink adjacent to the opening, said fingers being spaced apart, a nut screw-threaded on the nipple below the outer bottom surface of the sink, and a fluid seal between the nut and the outer bottom surface of the sink. 80

3. The combination of a sink having a substantially flat horizontal bottom and provided with a circular drain opening extending through the bottom, said opening immediately joining the inner bottom surface of the sink without an intervening recess, a nipple comprising a threaded portion extending below the sink bottom and radially extending separated fingers engaging the inner bottom surface of the sink adjacent to the opening, and a nut on the nipple below the outer bottom surface of the sink. 90

4. The combination of a sink having a substantially flat horizontal bottom and provided with a circular opening extending through the bottom, said opening immediately joining the inner bottom surface of the sink without an intervening recess, a nipple comprising a threaded portion extending below the sink bottom and radially extending separated fingers engaging the inner bottom surface of the sink adjacent to the opening, a nut on the nipple below the outer bottom surface of the sink, and a gasket intermediate the nut and the outer bottom surface of the sink. 105

5. The combination of a sink having a substantially flat horizontal bottom and provided with a circular drain opening extending through the bottom, said opening immediately joining the inner bottom surface of the sink without an intervening recess, a nipple comprising a threaded portion extending below the sink bottom and radially extending separated fingers engaging the inner bottom surface of the sink adjacent to the opening, a nut on the nipple below the outer bottom surface of the sink and a strainer of inverted dish shape secured to the nipple and provided with top perforations and side perforations adjoining the 110 120 125 130

sink surface, by means of which the entire fluid contents of the sink may drain through the nipple.

6. The combination of a sink having a substantially horizontal bottom provided with a drain opening, a nipple passing through the opening and having members engaging the inner bottom surface of the sink adjacent to the opening, said members extending above the normal inner surface of the sink, means for securing the nipple in position and for preventing escape of fluid around the nipple and provided with top perforations and side perforations so arranged that the entire fluid contents of the sink may pass from the sink through the strainer and the nipple.

7. The combination of a sink, or the like, having a substantially horizontal enameled inner bottom surface provided with a straight drain opening and without a recess intermediate the drain opening and the inner bottom surface of the sink, a nipple passing through the drain opening and having separated fingers resting on the inner bottom surface of the sink and a strainer covering the nipple and having top openings and side openings adjoining the inner bottom surface of the sink.

8. The combination of a sink, or the like, having a substantially horizontal enameled inner bottom surface provided with a straight drain opening and without a recess intermediate the drain opening and the inner bottom surface of the sink, a nipple passing through the drain opening and having separated fingers resting on the inner bottom surface of the sink and a strainer of inverted dish shape secured to the nipple and covering the nipple and having top openings and side openings adjoining the inner bottom surface of the sink.

9. The combination of a sink, or the like, having a substantially horizontal enameled inner bottom surface provided with a straight drain opening and without a recess intermediate the drain opening and the inner bottom surface of the sink, a nipple passing through the drain opening and having separated fingers resting on the inner bottom surface of the sink and a strainer covering the

nipple and having top openings and side openings adjoining the inner bottom surface of the sink, means for holding the nipple in position and a drain pipe connected to the 55 nipple.

10. The combination of a sink, or the like, having a substantially horizontal enameled inner bottom surface provided with a straight drain opening and without a recess 60 intermediate the drain opening and the inner bottom surface of the sink, a nipple passing through the drain opening and having separated fingers resting on the inner bottom surface of the sink and a strainer of inverted 65 dish shape secured to the nipple and covering the nipple and having top openings and side openings adjoining the inner bottom surface of the sink, means for holding the nipple in position and a drain pipe connected to the 70 nipple.

11. The combination with a sink having an enameled inner surface and a straight drain opening in the bottom of the sink, the opening immediately joining the inner bottom surface of the sink without any intervening recess, of a nipple passing through the opening and having a flange resting on the inner bottom surface of the sink, the flange being provided with an opening to permit 80 drainage of residual fluid, and an inverted dish shaped strainer secured to the nipple and having top openings and side openings adjoining the inner bottom surface of the sink.

12. The combination of a sink or the like having a substantially horizontal enameled bottom provided with a drain opening joining the inner bottom surface of the tub without an intervening recess, a nipple passing 90 through the opening and having a flange resting on the inner bottom surface of the sink adjacent to the opening, the flange being provided with a passage permitting drainage of residual fluid through the nipple, and a 95 drain pipe secured to the nipple.
